UNITED STATES PATENT OFFICE.

FRANK B. HARRISON, OF TOLEDO, OHIO.

DUST-GUARD.

1,171,045.

Specification of Letters Patent.

Patented Feb. 8, 1916.

Application filed May 21, 1915. Serial No. 29,469.

To all whom it may concern:

Be it known that I, FRANK B. HARRISON, a citizen of the United States, residing at Toledo, in the county of Lucas and State of 5 Ohio, have invented certain new and useful Improvements in Dust-Guards; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 In the operation of railway cars, it is important to protect the journals and journal boxes against abrasion and undue wear by reason of the access of dust, sand and other foreign matter to the interior of the journal 20 boxes. It is also important to prevent the escape and waste of oil from the journal boxes. The usual method of guarding against these difficulties is to provide the journal-box with a dust-guard arranged to 25 exclude the dust and prevent the escape of lubricant.

My invention relates to a device of this character and is designed to provide a dust-guard which shall be simple, cheap and 30 durable, and which will remain in its proper position and operative relation within the dust-guard chamber of the journal-box regardless of the wear of the journal-brass or the ordinary vicissitudes of railway service.

35 My invention is designed as an improvement upon the dust-guard patented to me by U. S. Letters Patent Number 752,164, dated February 16, 1904, and, more particularly, to furnish an elastic, channeled steel 40 ring of peculiar construction which shall tightly clasp the car-axle and which shall not leave an opening at the meeting opposed ends of the ring and which shall furnish a dust-proof joint when the ring is in service 45 position upon its axle.

To these ends my invention consists of the devices, construction and arrangement of parts hereinafter described, and shown and illustrated in the accompanying drawings, 50 in which—

Figure 1 is a perspective view of my device; Fig. 2, an edge-view of one of the blocks of my device showing the channeled spring ring hereinafter referred to, in cen-

tral transverse section, and Fig. 3, a perspective view of the ring hereinafter referred to, detached.

It should be understood that the device of the present invention is intended for use in connection with the journal-box such as is 60 in common use in connection with car-trucks, this journal box being provided with the usual chamber formed in the back portion of the box for the reception of the dust-guard. Since this journal-box and its dust-guard recess are well understood and as they constitute no part of the present invention they need not be here further illustrated or 65 described.

In the drawings 1 and 2 represent the two 70 equal parts of a dust-guard block or frame which may be regarded as a substantially square flat piece of board or other suitable material having centrally therethrough a circular hole 3 of slightly greater diameter 75 than the car axle to be embraced and being transversely divided in halves. Each margin of the opening 3 is slightly and equally countersunk, as at 4, thus forming an inwardly projecting circumferential tongue or 80 rib 5. The meeting edges of the parts 1—2 are provided with dowels, as indicated in dotted lines in Fig. 1, by which the block parts are removably held together.

6 is a steel sheet metal ring, U-shaped in 85 cross-section and open at one side. The channel of the ring receives the tongue 5 with a fit sufficiently loose to permit the rotation of the ring which, when in service position, tightly clasps and revolves with 90 its axle. The bottom of the channel of one of the meeting ends of a ring is, for a short distance, cut away, as at 7, leaving two forwardly projecting flaps 8 which are bent 95 outwardly slightly so as to receive between them and to overlap the sides of the opposite end of the ring. The breadth of the tongue 5 and the thickness of the metal flanges of the ring are such that when the parts are assembled the outer surfaces of 100 the flaps 8 lie only slightly within the planes of the surfaces of the parts 1—2.

It will be seen that when the parts here described are assembled in operative relation to their journal, the contractile stress 105 of the ring will prevent access of dust between the ring and its flaps and the axle, and between the overlapping contacting flaps 8

and the opposed ring-flanges, as well as between the contacting sides of the tongue and the ring-flanges.

Having described my invention, what I claim and desire to secure by Letters Patent of the United States, is—

1. A dust-guard comprising a two part frame having centrally therethrough a circular opening bounded by an inwardly projecting circumferential tongue, an open circumferentially channelled spring ring the channel of which takes and frictionally engages said tongue, the bottom of one end of said channel being cut away, the sides of 15 the ring forming flaps which overlap and

frictionally engage the sides of the opposed end of the ring.

2. In a device of the described character, an open spring ring, U-shaped in cross-section, one end of said spring having forwardly projecting flaps which overlap and frictionally engage the sides of the opposite end of the ring the bottom of the channel between said flaps being removed.

In testimony whereof I affix my signature in presence of two witnesses.

FRANK B. HARRISON.
